OR THE LIKE

Thomas A. Tanury, Riverside, R. I.

Application April 6, 1954, Serial No. 29,886

Term of patent 14 years

(Cl. D64—12)

To all whom it may concern:

Be it known that I, Thomas A. Tanury, a citizen of the United States, residing at Riverside, in the State of Rhode Island, have invented a new, original, and ornamental Design for an Alphabet for Forming Monograms or the like, of which the following is a specification, reference being had to the accompanying drawing, forming a part thereof.

Figure 1 is a face view of upper case letters of an alphabet for forming monograms or the like, embodying my new design.

Figure 2 is a side view of one of the letters of Fig. 1.

Figure 3 is a face view of lower case letters of an alphabet for forming monograms or the like, embodying my new design.

Figure 4 is a side view of one of the letters of Fig. 3.

I claim:

The ornamental design for an alphabet for forming monograms or the like, as shown.
